DESIGN FOR A DISPENSER CLOSURE TOP OR SIMILAR ARTICLE

Rudolph Bernhardt, Chicago, Ill.

Application June 26, 1939, Serial No. 85,692

Term of patent 7 years

To all whom it may concern:

Be it known that I, Rudolph Bernhardt, a citizen of the United States and resident of Chicago, in the county of Cook and State of Illinois, have invented a new, original, and ornamental Design for a Dispenser Closure Top or Similar Article, of which the following is a specification, reference being had to the accompanying drawing, forming part thereof.

In the drawing,

Figure 1 is a perspective view of a dispenser closure top or similar article showing my new design;

I claim:

The ornamental design for a dispenser closure top or similar article, substantially as shown.

RUDOLPH BERNHARDT.
